STATIC ELIMINATOR

Toshio Saito, 12-11, 7-chome, Ikagami, Ota-ku,
Tokyo, Japan

Filed Sept. 1, 1972, Ser. No. 285,866

Term of patent 14 years

Int. Cl. D8—99

U.S. Cl. D26—1 L

FIG. 1

FIG. 2

FIG. 3

FIG. 4

FIG. 5

FIG. 6

FIG. 7

FIG. 1 is a front end view of a static eliminator embodying my new design;

FIG. 2 is a rear end view of the static eliminator shown in FIG. 1;

FIG. 3 is a top view of the static eliminator shown in FIGS. 1 and 2;

FIG. 4 is a bottom view of the static eliminator shown in FIG. 3;

FIG. 5 is a side view of the static eliminator shown in FIGS. 3 and 4;

FIG. 6 is a sectional view of the static eliminator shown in FIGS. 3 to 5, taken along line 6—6 of FIG. 3; and

FIG. 7 is a perspective view of the static eliminator shown in FIGS. 1 to 6.

The side of the static eliminator not shown in FIG. 5 has an appearance identical with the appearance of the side shown in FIG. 5.

I claim:

The ornamental design for a static eliminator, substantially as shown and described.
